UNITED STATES PATENT OFFICE.

PATRICK KANE, OF NORTH BROOKFIELD, MASSACHUSETTS.

FOUNTAIN-BRUSH.

1,032,549.

Specification of Letters Patent.

Patented July 16, 1912.

Application filed January 30, 1911. Serial No. 605,373.

To all whom it may concern:

Be it known that I, PATRICK KANE, a citizen of the United States, residing at North Brookfield, in the county of Worcester and State of Massachusetts, have invented a new and useful Fountain-Brush, of which the following is a specification.

This invention relates to a brush, and while capable of application to many kinds of brushes, is particularly valuable when applied to those brushes generally used in shoe factories by edge trimmers.

The principal objects of the invention are to provide a construction for supplying water or other fluid to a brush from which the brush proper is entirely removable so that without unfastening any parts or interfering with the construction of the device in any way the attachment can be detached from a brush and applied to another one; to provide a simple and convenient construction for applying water to the brush along one edge thereof in such a way as to make it necessary to use only a small amount of water to thoroughly wet the brush, and at the same time to apply the water in such a way that the life of the brush, particularly when the invention is applied to edge trimmers' brushes, will be greatly lengthened.

The invention also involves an improved construction of clip whereby the device is very simply and conveniently attached to the brush, an improved form of valve operating means, and other details of construction as will appear hereinafter.

Reference is to be had to the accompanying drawings, in which —

Figure 1 is a side elevation view showing how the brush can be used as an edge trimmer's brush and illustrating a preferred embodiment of this invention; Fig. 2 is a plan of the brush. Fig. 3 is a bottom plan thereto; Fig. 4 is a sectional view of the same on the line 4—4 of Fig. 2; and Fig. 5 is a side view partly in section, the brush being detached.

The invention is shown as applied to an ordinary edge trimmer's brush B as is commonly used in boot shops by edge trimmers for wetting the edge of the sole before the final trimming operation in order to facilitate that operation and secure a smooth trimmed edge. This brush is ordinarily provided at its inner end with a handle of slightly curved form but of uniform cross section throughout. The attachment is

shown as comprising a sheet metal plate 10 adapted to rest on the back of the brush and having along one edge an inwardly extending flange 11 but provided near that flange with a spring clip 12 projecting inwardly at its end to more firmly clamp the back of the brush. On the other edge is a flange 13 provided with a clip 14 at one end slightly separated and a clip 15 at the other end supported nearer to the plate 10 as is the case with the clip 12, opposite which it is located. These clips are formed integrally with the plate and simply bent up so that they resiliently hold the attachment on the back of the brush and preferably constitute the only means of securing it in position. The two clips 12 and 15 project inwardly beyond the edges of the flanges 11 and 13 in order to come into the path of the bristles of the brush and prevent the brush being removed by sliding the holder off the outer or forward end of the back. By this construction these clips are made in such a way that the attachment will remain on any part of the brush without taking any particular pains to secure it in position, but can be readily removed by slipping it backwardly along the handle.

On the plate is located a cylindrical casing 16 having a perforated partition 17 therein constituting a valve seat. For closing the perforation in this partition a valve 18 is provided consisting of a rubber washer or the like mounted on a valve stem 20. This valve stem extends down in the cylinder and is provided with an L-shaped extension 21 projecting out through a hollow tubular projection 22 on the casing. This projection 21 terminates in a plate 23 by which the valve is manipulated and the projection is provided with an enlargement 24 which is connected with the projection 22 by a section 25 of rubber hose or the like to prevent leakage. To normally hold the valve down on its seat so as to close the port in the partition a spring 26 is provided resting thereon and held in position by a screw-threaded cap 27. This cap is provided with a hollow projection 28 to the end of which is connected a supply hose 29, from a water supply system or from an elevated receptacle.

The bottom of the cylinder is provided with a projection 30 shown as of L-shape extending outwardly and then down along the side of the flange 13, and having at the lower end thereof a horizontal tube 31 hav-

ing a number of perforations 32 along the inner side thereof. This tube is located at the bottom of the flange and also at the bottom of the brush back when the brush 5 is in position in the attachment and the perforations are located on the inner side so as to project streams of water parallel with the surface of the brush back from which the bristles come. It is preferably of a 10 length substantially equivalent to the length of the bristled surface of the brush so that it will discharge water along the whole length of bristles. The end of this latter hollow tube is provided with a removable 15 screw-plug closure 33 which can be removed to clean out the tube if it gets clogged up.

In operation it will be understood of course that the spring normally holds the valve on its seat so that no water can flow 20 through. The operator grasps the brush handle as shown in Fig. 1 with his finger on the plate 23 so as to permit water to pass through and flow out of the perforations in the hollow tube. In this way the 25 brush is thoroughly wet and there is no danger of it getting too moist as the supply of water is constantly within the control of the operator. It is found in practice also that by the use of this device the operation 30 of wetting the shoe soles is very much facilitated by a much neater and better procedure.

The ordinary course is to have a pan of water handy and to dip the brush in it from 35 time to time, but particles of dirt get into the water and the brushes used do not hold enough water when dipped in this way to enable them to be used to go all the way around a shoe sole with one dipping. Conse- 40 quently, the shoe sole is wet unevenly in its different parts and time is occupied dipping the brush two or three times during the operation. Moreover, the water is scattered around in the vicinity of the support for the 45 shoe. By the present invention all these difficulties are avoided as the shoe sole is uniformly moistened by a single motion of the hand of the operator and yet smaller quantities of water are used than before, and 50 the water is always clean. At the same time when the brush is worn out it can be removed from the holder and a new one applied with the expenditure of practically no time. On account of the even wetting of 55 the brush and the fact that the brush back

is not plunged into a pan of water it has been found by experience that the brushes last much longer than they have done under the old conditions.

The different parts of the device can be 60 put together by screw threads, brazing, soldering, or any other desired way, but the cap 27 preferably is screw-threaded into the cylinder 16 in order that the valve and spring may be readily reached for cleaning 65 purposes and repair.

While I have illustrated and described a preferred embodiment of the invention and shown it as applied to a particular type of brush, I am aware that the invention can 70 be carried out with many modifications, and that it can be applied to many other types of brushes than the one illustrated. Therefore I do not wish to be limited to all the 75 details of construction herein shown and described, or to the particular type of brush shown, but

What I do claim is:—

In a device of the character described, the combination of a brush having a handle at 80 one end, a fountain attachment provided with means for clamping it to the back of the brush adjacent to the handle, said attachment embodying a plate, a brush sprinkling tube, a vertical casing mounted on the 85 plate and connected at its lower end to said sprinkling tube, a valve casing attached to the upper end of said cylinder and inclosing a valve disk and means for normally pressing it downwardly, a water supply attachment to said valve casing, a partition be- 90 tween the valve casing and the lower casing, provided with an opening, a lateral tube at- 95 tached to the lower casing, a lever extending into the lower casing through said tube and pivoted in said tube, the inner end of the lever being bent upwardly and attached to the aforesaid valve disk and the outer end of the lever being provided with a finger piece adjacent to the handle portion of the 100 brush, and means for making a water tight joint between the lever and the tube in which it is pivoted.

In testimony whereof I have hereunto set my hand, in the presence of two subscribing 105 witnesses.

PATRICK KANE.
